[57] CLAIM

The ornamental design for a combined x-ray control board and support structure for medical treatment, as shown.

DESCRIPTION

FIG. 1 is a front, top and right side perspective view of a combined x-ray control board and support structure for medical treatment, showing our new design;
FIG. 2 is a reduced front elevational view thereof;
FIG. 3 is a right side elevational view thereof;
FIG. 4 is a top plan view thereof;
FIG. 5 is a rear elevational view thereof;
FIG. 6 is a left side elevational view thereof; and,
FIG. 7 is a bottom plan view thereof.

FIG. 1
